UNITED STATES PATENT OFFICE

FREDERICK J. BERGS, OF MILWAUKEE, WISCONSIN, ASSIGNOR TO BERGS MANUFACTURING COMPANY, OF MILWAUKEE, WISCONSIN

SAFE

Application filed November 13, 1930. Serial No. 495,404.

This invention relates to improvements in safes and more particularly to a safe which is adapted for use as an altar tabernacle.

One of the objects of the present invention is to provide a safe of the above character wherein improved mechanism is used for locking the closure doors of the safe and wherein this locking mechanism is released upon insertion of a key in the lock so that the doors can be readily moved to an open position, and also includes mechanism operated upon the opening movement of the door for closing the space which the doors occupy, when in a closed position, at the front of the safe.

Another object of the present invention is the provision of a safe of the above character provided with novel locking means, together with novel means for releasing the locking means upon insertion of the key in the lock, as well as means for providing suitable buffer means for restraining the movement of the doors while being moved to a closed position.

With the above and other objects in view, the invention consists in the novel features of construction, the combination and arrangement of parts hereinafter more fully set forth, pointed out in the claims and shown in the accompanying drawings wherein:

Figure 1 is a horizontal sectional view looking upwardly onto the bottom portion of the safe, with the doors in a closed position;

Figure 2 is a detailed plan view showing the doors in an open position;

Figure 3 is a detailed top plan view;

Figure 4 is a detailed section on the line 4-4 of Figure 1;

Figure 5 is a detailed section on the line 5-5 of Figure 4; and,

Figure 6 is a side elevation of the key member with parts broken away and illustrated in cross section.

Referring more particularly to the drawings, 1 indicates the outside housing of the safe which is substantially opened at the front thereof with inwardly projecting fanciful side portions 2, the main body 3 of the safe is arranged in the outside housing 1, as

shown in Figure 1, and opens between the fanciful side portions 2 and this open side is normally closed by means of the movable door members 4 and 5. At the top and bottom of the door members 4 and 5, I provide connecting plates or arms 6, the inner ends of which curve inwardly and are mounted upon a main supporting post 7 which carries a bevel gear 8 adapted to mesh with a similar gear 9 on the lock shaft 10. The lock shaft 10 is rotatably mounted in suitable bearings 11, depending from the bottom portion 12 of the body 3.

The lock shaft 10 is provided at one end with a reduced portion 13 which is received within the recessed end 14 of the rotatable barrel 15. The barrel 15 is rotatably mounted within a guide member 16, as shown in Figure 4.

Slidably mounted upon the locking shaft 10 is a sleeve 17 having an annular cap-like portion 18 adapted to engage over the fingers 19 which are arranged at the inner ends of brackets 20 carried by the lower plates 6. The locking shaft 10 is also provided with a longitudinal bore and arranged within this bore is an actuating rod 21, the inner end of which bears against the finger 22 of rod 23 which curves around the supporting post 7, as shown in Figure 1, and has its other end pivotally connected to a link 24 which in turn is connected to a vertical shaft 25 having at its upper end a link 26 pivotally connected to a rod 27. The rod 27 is attached to an arm 28 on a rotatable sleeve 29. The sleeve 29 carries a rockable arm 30 having oppositely projecting hook portions 31 which engage over stop pins 32 carried by the upper plates 6.

Normally, the rockable arm 30 is retained in a locked position by means of a coil spring 33, but when the rod 21 is reciprocated inwardly toward the bearing post 7, the rod 23 will rock the link 24 and rotate shaft 25, which in turn will rock the link 26, reciprocating rod 27 and rotating sleeve 29 to release the catch members 31 from the pins 32.

Arranged within the locking barrel 15 is a central member 34 which provides an annular chamber 35 for receiving the barrel 36 of

the key, and at the inner end of the annular chamber 35 are the pins 37 carried by the head 38 which supports a reciprocating pin 39 adapted to engage the upper end of rod 21.

Thus, when the barrel of the key is inserted in an annular chamber 35, the inner end of the barrel will engage the pins 37 forcing the same longitudinally in the barrel 15, this movement reciprocates the rod 21 for unlocking both the upper and lower sets of plates 6. The lowermost set of plates 6 is released through the longitudinal movement of sleeve 17 on the locking shaft 10, as member 10 is provided with a longitudinal slot 40 in which is slidably arranged a pin 41 carried by sleeve 17. The cylinder or barrel 15 is retained against rotative movement when the key is withdrawn from the lock by means of a spring member 42 carried by the housing 16 and projecting into a slot 43 along one side of the cylinder 15, as shown in Figure 4.

The bevel gear 9 is carried by the inner end of locking shaft 10 and in order to impart movement to the door members 4, it is necessary to rotate the cylinder 15 and this can be done after the key has been inserted in the annular housing 35 by means of a longitudinal flange 44 carried by the barrel of the key, and adapted to be received in the slot 43. It will be noted that as the key is pushed into the cylinder 15, the flange 44 will engage the spring 42 and move the same out of the slot 43, thus permitting rotative movement of the cylinder 15, and in turn through the clutch members 13 and 14, impart a rotative movement to barrel 10. The key member is provided with a substantially flat wide head, as shown in Figure 5, so that the same can be readily grasped by the fingers to impart considerable turning force to the key after being inserted in the cylinder 15.

Ordinarily, when the doors 4 and 5 are in a closed position as shown in Figure 1, they occupy the space indicated at A, which is disposed between the forward edge of the bottom member 12 and the upright portion 46 of the outside housing. Therefore, when the doors are moved to an open position, the space A is left open, and in order to provide a neat appearance for the interior of the safe when the doors are in an open position, we provide means for closing this space A by means of a movable plate 47. Connected to the movable plate at spaced points are the longitudinal movable rods 48, slidably mounted in spaced bearings 49 carried by the brackets 50, and the inner ends of rods 48 are connected by means of a cross piece 51. Normally, the plate 47 which is arcuate in shape, as shown in Figure 2, is retained in a retracted position against the guide brackets 52 by means of coil springs 53, embracing the rods between the bearing sleeves 49 with one end engaging the stop pins 54, and the other end bearing against one of the sleeves

49. These springs normally urge the rods inwardly to retain the plate 47 in an inoperative position against brackets 52.

In order to provide means for actuating rods 48 and moving the plate 47 to its forward position for closing the space A, I provide a pivoted arm 55, one end of which has a bearing head 56 engaging cross piece 51, while the other end carries a pin 57 slidably mounted in slot 58 formed in the bracket plate 59.

From this, it will be apparent that when the door members 4 and 5 are moved to an open position through the movement of plates 6, the bracket plate 59 which is carried by one of the lowermost plates 6, as shown in Figures 1 and 2 will cause the arm 55 to be rocked upon its pivot engaging the head 56 thereof with a cross piece 51, and urging the rods 48 outwardly, moving the plate 47 to a position which will close the space A.

From the above description taken in connection with the accompanying drawings, it will be apparent that we have provided a tabernacle safe which will be maintained in a securely locked position until released by an authorized person who has possession of the key, and wherein the doors can be inwardly moved to an open position when unlocked by the turning movement of the key and can be moved to a closed position through a reverse turning movement of the key and immediately prior to the finish of the closing movement of the doors, the movement is slightly retarded by means of yieldable arms 59 and 60 which are carried by the uppermost plates 6, as shown in Figure 3. These arms are so arranged as to have the inner ends thereof frictionally engage each other and retard the inner movement of the doors, so as to reduce to a minimum any noise during the time the doors are being brought to a completely closed position.

As soon as the doors are brought into a closed position so that the inner edges thereof overlap as shown at 61 in Figure 3, the hook members 31 will engage the locking pins 32 on the top plate 6 and this movement will actuate rods 27 and 28 to impart a longitudinal movement to rod 21 so as to move the cap member 18 over fingers 19 as shown in Figure 1, it being understood that the key has been slightly withdrawn so as to permit the pins 37 to be returned into the annular housing 35. As soon as the key is entirely removed, the spring member 42 will return to its position within the slot 43, so as to retain the locking cylinder against rotative movement.

The housing 1 can be made of any fanciful material and the front side portions 2 can also be made fanciful as well as the doors 4 and 5, and it is believed that we have provided a safe which cannot be easily opened without the use of a proper key.

I claim:

1. A safe structure including movable doors adapted to be swung to an open or closed position, means for locking said doors in a closed position, a rotatably mounted locking cylinder, means forming operative connection between the cylinder and the doors, whereby rotation of the cylinder will move said doors to an open or closed position, a reciprocating rod movable longitudinally of the cylinder, means forming operative connection between the rod and the locking means, and means adapted to be engaged by a key inserted in the locking cylinder whereby to move said rod longitudinally for releasing said locking means to permit open movement of the doors.
2. In a safe structure, a bottom therefor and an upright forward structure spaced from the bottom, movable doors normally disposed in the space between the bottom and said upright forward structure when in a closed position, means for moving said doors to an open position, and means actuated by the opening movement of the doors for closing the space between the bottom and said upright structure when the doors are in an open position.
3. In a safe structure, a pair of doors adapted to be moved to an open or closed position, connecting plates attached to the top and bottom portions of said doors, a rotatably mounted cylinder lock, means forming operative connection between the cylinder lock and the plates for imparting opening or closing movement to the doors upon rotative movement of the cylinder, bracket plates carried by one set of plates having inwardly projecting fingers, a movable sleeve carrying a cap to engage said fingers when the doors are in a closed position for retaining them against opening movement, means actuated by the insertion of a key in said locking cylinder for disengaging said cap from the fingers, and means for retaining the cylinder against rotation when the key is withdrawn.

In testimony that I claim the foregoing I have hereunto set my hand at Milwaukee, in the county of Milwaukee and State of Wisconsin.

FREDERICK J. BERGS.
